PUNCH FOR RIMLESS CANS

Frazier O. Brooks, Ca-Vel, N. C.

Application May 21, 1952, Serial No. 289,165

4 Claims. (Cl. 30—16)

1

This invention relates to new and useful improvements in can punches and the primary object of the present invention is to provide a punch for rimless cans that is manually forced downwardly into the top of a can in order to form a triangular pouring opening in the top of the can.

Another very important object of the present invention is to provide a can punch including a pointed puncturing element having an angulated extremity and beveled side edges, whereby the extremity will form a small aperture in a can top through which the beveled side edges will pass to form the desired triangular pouring opening or vent.

A further object of the present invention is to provide a can punch of the aforementioned character wherein the puncturing element is formed at one end of an elongated rigid strip, and comprises an offset portion having limbs which are inclined relative to the strip with the pointed extremity parallel to the strip, thereby facilitating convenient use of the punch in forming openings in the tops of rimless cans.

A still further aim of the present invention is to provide a can punch for rimless cans, that is extremely simple and practical in construction, strong and reliable in use, neat and attractive in appearance, efficient and durable in operation, inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is an elevational view of the present invention and showing the same in use for punching and opening in a can, the can being shown partially in elevation and partially in cross section for the convenience of explanation;

Figure 2 is a plan view of a can, whose top wall is provided with an opening formed by the present punch;

Figure 3 is an elevational view of the present invention;

Figure 4 is an enlarged detailed fragmentary vertical sectional view taken substantially on the plane of section line 4—4, Figure 3;

Figure 5 is an enlarged detailed horizontal sectional view taken substantially on the plane of section line 5—5 of Figure 3.

Referring now to the drawings in detail, wherein for the purposes of illustration, there is dis-

2

closed a preferred embodiment of the present invention, the numeral 10 represents an elongated rigid, shank-forming strip having its outer end bent to form an offset end portion or puncturing element designated generally by the numeral 12. The puncturing element 12 includes an inner limb 14 and an outer limb 16, both of which are inclined relative to the shank-forming strip.

Limb 16 is pointed and isosceles triangular, and 10 the side edges 18 and 20 of the limb 16 are beveled and meet at the free pointed extremity 22 of the limb which is bent downwardly, as at 24, to a position spaced parallel to the shank as shown best in Figure 4.

15 A bottle cap removing tongue 26 is struck from the limb 14 and extends laterally from the opposite side of strip 10 then the offset portion 12. The free end of tongue 26 is bent downwardly to form a flange 28 for engaging under the edge of 20 a bottle cap over which is disposed the limb 14. The limb 14, tongue 26 and flange 28 will coact to define a channel 30 (Figure 4) that will receive 25 a cap with the limb 14 resting on the top of the cap, the tongue 26 resting against the flange of 25 the cap and the lug or flange 28 engaged under the flange of the cap. As the shank is manually raised with limb 14, rocking on the cap, the flange 28 will pull the cap from the bottle to which it is attached.

30 The side edges of the limb 14 are integrally formed with stop lugs or shoulders 32 and 34 that project laterally outwardly from the side edges 18 and 20 to engage the top of a can and thereby limit downward movement of the end portion 12 through the top of the can.

35 An elongated hand grip 36, disclosed perpendicular to strip 10, is provided with a central slot at its under surface in which the upper end of shank-forming strip 10 is suitably fixed. The 40 ends of the hand grip 36 are smoothly rounded and the top surface of the hand grip is also smoothly rounded or convex to provide smooth surfaces for a user's hand.

In practical use of the invention as a punch 45 for rimless cans C the shank 10 is horizontal and the user forces downwardly on the grip 36 so that the extremity 22 will form a small aperture in the can top. Continued downward pressure on the hand grip will cause the edges 18 and 20 to enter the aperture formed by the extremity 22, thereby forming a V-shaped opening O in the can top. The lugs 32, 34 will engage the can top to limit penetration of portion 12.

It is preferred that the tool be held over the 55 can with portion 12 positioned as shown in Figure

1, so that the opening O will be disposed in the top of the can and taper toward the peripheral edge of the can top. This will result in a substantially V-shaped stream of liquid being poured from the can with the apex of the V-shaped stream facing downwardly, a feature not possible with the commonly available can punches which require the can having a rim.

Having described the invention, what is claimed as new is:

1. A can punch comprising an elongated flat shank terminating in an offset end portion having an outer limb, said outer limb being pointed and having beveled side edges, the extremity of said outer limb being bent to a position parallel to said shank and forming a penetrating element that will permit an aperture to be punched in a can through which the beveled side edges of the outer limb will pass.

2. A can punch comprising an elongated flat shank terminating in an offset end portion having an outer limb, said outer limb being pointed and having beveled side edges, the extremity of said outer limb being bent to a position parallel to said shank and forming a penetrating element that will permit an aperture to be punched in a can through which the beveled side edges of

the outer limb will pass, said offset end portion also having an inner limb considerably wider than said outer limb to include side edges projecting laterally from the outer limb that function as stops limiting penetration of said outer limb in a can top.

3. A can punch comprising an elongated flat rigid shank terminating in an offset portion at one end, a hand grip attached to the other end 10 of said shank, said offset portion including inner and outer limbs, said outer limb being pointed and having beveled side edges meeting at the extremity of said outer limb, both of said limbs being inclined relative to said shank, the pointed 15 extremity of said outer limb being bent downwardly to a position parallel to said shank, and stop lugs integrally formed with the side edges of said inner limb projecting laterally outwardly from the beveled side edges to engage the top 20 of a can and limit the penetration of the inner limb in a can top.

4. The combination of claim 3 wherein said hand grip comprises an elongated smoothly rounded member centrally secured to the shank 25 and disposed perpendicular to the shank.
